UNITED STATES PATENT OFFICE.

OTTO FRICK, OF STOCKHOLM, SWEDEN.

ELECTRIC TRANSFORMER-FURNACE.

No. 898,618.

Specification of Letters Patent.

Patented July 21, 1903.

Application filed November 16, 1905. Serial No. 287,627.

To all whom it may concern:

Be it known that I, OTTO FRICK, a subject of the King of Sweden, and resident of Saltsjöbaden, Stockholm, Sweden, have invented a new and useful Improvement in Electric Transformer-Furnaces, of which the following is a specification, reference being had to the drawing accompanying and forming a part hereof.

This invention relates to improvements in electric transformer-furnaces. In such furnaces the melting space forms as well known an annular crucible around a central iron-core, the said crucible being during the melting-process kept closed by a cover. In order to obtain a uniform melting in the whole furnace all parts of the same must be accessible and be uniformly charged. For this purpose the cover of the crucible has heretofore been carried out in a number of sectors removable independently of each other. Such devices have, however, the disadvantage that on account of the great number of joints and the repeated removals of the cover-sections openings will be easily formed between the latter, such openings causing losses of heat. Further it is not possible in the transformer-furnaces heretofore known to obtain a uniform distribution of the material to be charged in the whole crucible if the said material be charged in non-melted condition.

The object of the present invention is to remove the said disadvantages, and it consists, chiefly, in that the cover for the melting space is rotatably supported whereby it will be possible to observe all parts of the melting space and to charge the same uniformly through a single or some few openings. The cover may suitably consist of a single piece so as to obviate cross-joints the tightening of which always is connected with great difficulties.

In the accompanying drawing, Figure 1 shows a vertical section, and Fig. 2 shows a plan view of an electric furnace forming one form of embodiment of my invention.

Referring to the drawings, 1 represents the masonry in which the crucible 3 is formed, 2 the cover of the latter, 4 the primary winding of the furnace, 5 the iron-core of the same, 6 the charge-opening of the cover 2, and 7 rollers supporting the cover 2 so that the latter may be rotated. By the

said arrangement of the cover will be gained 55 that by rotating the cover by hand or mechanically all parts of the crucible may be easily observed and material may be conveniently charged into any part of the melting space.

The charge-opening may be closed by means of a cover which may be secured by a hinge or, preferably, to a small car running on a track, so that the said cover may easily be moved to the side.

In using a movable cover having only one charge-opening the furnace may easily be brought to work air-tightly by providing a water- or sand-seal between the movable and the stationary parts, the charging being accomplished by a hopper having an upper and a lower valve, as is usual in gas-generators, or by a screw or the like, in which case the tightening is effected by the material itself.

The cover 2 may be constructed either as a 75 usual arch-vault resting partly on an outer and partly on an inner ring, or as a cupola resting only on an outer ring, and it may be supported by rollers journaled at the circumference of the cover, as is shown in Fig. 1. 80

In the construction of the mechanical parts of the furnace care obviously must be taken that no annular circuits are formed around the core by the metal used in the construction of the furnace. Tracks and the like at the cover must, therefore, be provided at suitable points with insulating joints in order to prevent secondary electric currents in the same.

I am aware that furnaces having the cover 90 and the masonry forming the melting space rotatable relatively to each other are well known, and I, therefore, do not claim such furnaces broadly, but so far as I am aware electric transformer furnaces have never 95 been constructed in such a way and I, therefore, claim the above arrangement in combination with electric transformer furnaces.

Having now particularly described my invention, what I claim as new and desire to secure by Letters Patent is:

1. An electric transformer-furnace having a masonry forming a melting space, and a cover rotatable relatively to the said masonry, substantially as and for the purpose 105 set forth.

2. An electric transformer-furnace having a stationary masonry forming a melting

space, a cover closing the said melting space, and rollers supporting the said cover in such a manner as to allow of it being rotated about a central axis, substantially as and for the 5 purpose set forth.

3. In an electric transformer-furnace the combination of a stationary masonry forming a melting space, a rotatably journaled cover for the said melting space, said cover 10 having a charge-opening, and a cover closing

the said opening, substantially as and for the purpose set forth.

In testimony whereof I have signed my name to this specification in presence of two subscribing witnesses.

OTTO FRICK.
